UNITED STATES PATENT OFFICE.

JOHN R. MCRAE, OF ALBANY, NEW YORK, ASSIGNOR TO MERGENTHALER LINOTYPE COMPANY, A CORPORATION OF NEW YORK.

LINOTYPE-MACHINE.

1,088,713.

Specification of Letters Patent.

Patented Mar. 3, 1914.

Application filed April 5, 1913. Serial No. 759,141.

To all whom it may concern:

Be it known that I, JOHN R. MCRAE, a subject of the King of the United Kingdom of Great Britain and Ireland, residing at 5 Albany, in the county of Albany and State of New York, have invented certain new and useful Improvements in Linotype-Machines, of which the following is a specification, reference being had therein to the accompanying drawing.

My invention relates to linotype machines, such for instance as are represented in Letters Patent of the United States to O. Mergenthaler, No. 557,000, wherein a 15 linotype or slug is cast in a slotted mold, the latter being pressed at its front against a composed line of matrices, and at its rear by the mouth of the melting pot, from which the molten metal is delivered. In 20 order to secure the proper operation of the parts, and the production of slugs of the exact height required, it is necessary that the two faces of the mold should be closed tightly against the matrices and the pot respectively, and further, that the matrices be crowded tightly against the members whereby they are sustained in line.

It sometimes occurs in practice, and particularly at the hands of an inexperienced or careless attendant, that the various devices mentioned are hindered from closing together properly, as for instance if the matrices are not properly alined, or if the mold carrier or wheel does not reach its final position, or because of the accidental accumulation of metal on the parts, or for other reasons. In such event, and if the pump is permitted to act, there will be a "squirt", and the molten metal will be ejected into the 40 operative parts in such manner as to prevent their proper action.

The object of the present invention is to prevent the action of the pump, whenever the pot fails to close tightly against the 45 mold, or the mold fails to close tightly against the matrix line. Similar devices are presented in Letters Patent of the United States to G. A. Vassberg, No. 659,863, and my invention is in effect an improvement on 50 the mechanism therein set forth, and is intended to simplify and render more certain the action of the parts. The principal distinction involved is the mounting of the pump stop on the movable pot itself, thereby

insuring a more convenient arrangement and greater accuracy in action.

In the accompanying drawings, I have shown my invention by way of illustration and in preferred form, and as applied to the specific type of machine referred to, but obviously many changes and variations may be made therein, and in its mode of application, which will still be comprised within its spirit. Generally speaking, I desire it to be understood that I do not limit myself to any specific form or embodiment, except in so far as such limitations are specified in the claim.

In the drawings: Figure 1 is a side view, partly in vertical section, of the casting mechanism, etc., with my invention embodied therein; Fig. 2 is a perspective view of a portion of the pump lever and connected parts; and Fig. 3 is a side view showing the stop in action.

Referring to the drawings, the matrix line X is supported as usual by the elevator Y in operative relation to the mold A carried by the mold wheel B, which latter is mounted on a horizontally sliding support, so that the 75 mold may be carried forward against the matrix line in order to force the latter against the forward wall of the elevator, thus insuring its exact alinement and also a close joint between it and the mold.

The melting pot C is arranged to swing forward and backward to and from the mold, these movements being controlled by the cam D. The pot is provided with a mouth C¹ and with the pump plunger E, 90 by which the delivery of the metal is effected. The plunger E is moved by the lever F, operatively to inject the metal by the spring G, and to its upper or normal position by the cam H. The matrix line X 95 is lowered by the elevator Y into position in front of the mold A, after which the mold and the pot C advance, the parts being thus crowded tightly together, so that a close joint is maintained both at the front 100 and rear of the mold.

The parts so far described, and their mode of operation, are or may be substantially similar to those described in the previously-mentioned Letters Patent, or as embodied 105 in the ordinary commercial linotype machine.

In applying my invention, I provide a

projecting stop K, and mount the same on the cover or upper portion of the movable pot C. The stop is normally located immediately below the arm or dog J connected 5 to the lever F (see Fig. 3,) in such manner as to prevent the descent of the lever and consequently the injection of the molten metal into the mold. The dog J is preferably pivotally connected to the lever F, and 10 a spring J¹ is provided to hold it in its normal position and to permit a slight elastic yield when the dog contacts with the stop.

The operation of the parts will now be 15 clearly understood. If the matrix line X, the mold A, and the pot mouth C¹ are closed to their operative positions, the stop K on the pot C shifts with the latter and is moved from under the dog J, thereby 20 permitting the downward movement of the lever F and the injection of the metal, in the customary manner. These positions of the parts are shown in Fig. 1. If, however, the pot is kept for any reason from going 25 forward to its proper position, the stop K remains under the dog J, and consequently the downward action of the lever F is arrested and the injection of the metal is prevented. These positions of the parts are 30 shown in Fig. 3. Anything which hinders either the matrices, the mold, or the pot

from assuming their proper operative relations, thus obstructs the action of the pump, and thereby averts the formation of a defective slug, or a squirt, or the delivery 35 of molten metal among the parts of the machine.

As previously stated, I have shown my invention in preferred form and by way of example, and as applied to a particular 40 type of machine. However, many modifications and variations thereof will suggest themselves to those skilled in the art without departure from its scope.

Having thus described my invention, its 45 construction and mode of operation, what I claim and desire to secure by Letters Patent of the United States, is as follows:

In a linotype machine, the combination 50 of the movable pot and the pump lever therefor, the said pot being provided with a fixed stop or abutment which in one position of the pot engages the pump lever and locks it against action and in another position of the pot frees the pump lever and 55 permits it to operate.

In testimony whereof I have affixed my signature in presence of two witnesses.

JOHN R. MCRAE.
